GUN RACK

Albert Del Pozo, New York, N. Y.

Application February 14, 1948, Serial No. 144,502

Term of patent 14 years

(Cl. D80—9)

To all whom it may concern:

Be it known that I, Albert Del Pozo, a citizen of the United States of America, residing in New York city, county of New York, and State of New York, have invented a new, original, and ornamental Design for a Gun Rack, of which the following is a specification, reference being had to the accompanying drawing, forming part thereof, wherein:

I claim:

The ornamental design for a gun rack, substantially as shown.

ALBERT DEL POZO.
